UNITED STATES PATENT OFFICE.

WALTER J. KOHLER, OF SHEBOYGAN, WISCONSIN, ASSIGNOR TO J. M. KOHLER SONS COMPANY, OF SHEBOYGAN, WISCONSIN, A CORPORATION OF WISCONSIN.

DESIGN FOR A LAVATORY.

No. 37,543.

Specification for Design.

Patented Sept. 12, 1905.

Application filed June 30, 1904. Serial No. 214,806. Term of patent 14 years.

To all whom it may concern:

Be it known that I, WALTER J. KOHLER, a citizen of the United States, residing in Sheboygan, in the county of Sheboygan and State of Wisconsin, have invented a new, original, and ornamental Design for Lavatories, of which the following is a specification, reference being had to the accompanying drawings, which are a part of this specification.

Figure 1 of the drawings is a front per-

spective view of a lavatory, showing my new design; and Fig. 2 is a rear perspective view thereof.

I claim—

The ornamental design for a lavatory, as shown.
